GEORGE W. CHRISTOPH, OF WAREHOUSE POINT, CONNECTICUT, ASSIGNOR TO STERLING BLOWER COMPANY, OF HARTFORD, CONNECTICUT, A CORPORATION OF CONNECTICUT.

PNEUMATIC POWER-BOAT.

1,265,997.

Specification of Letters Patent. Patented May 14, 1918.

Application filed October 16, 1916. Serial No. 125,869.

To all whom it may concern:

Be it known that I, GEORGE W. CHRISTOPH, a citizen of the United States of America, residing at Warehouse Point, in the county 5 of Hartford and State of Connecticut, have invented certain new and useful Improvements in Pneumatic Power-Boats, of which the following is a specification.

This invention relates to improvements in 10 pneumatic propelling and steering means for power boats or other vessels.

Pneumatic propulsion of boats has been accomplished, heretofore, in various ways. There are marked advantages in propelling 15 boats pneumatically once a satisfactory arrangement of the propelling means is found, and this invention is concerned particularly with an efficient and advantageous structural arrangement for pneumatically propelling a 20 boat, which arrangement is suitable for practical use.

The broad object of the invention is to provide an efficient and usable pneumatically propelled boat characterized by eliminating those operable parts of a boat which 25 normally churn the water and thus disturb the passage of the boat therethrough.

An object of the invention is to provide a 30 pneumatically propelled boat having at the bow thereof an air intake and at the stern an air discharge, both intake and discharge being arranged above the gunwales of the boat, a conduit connecting the intake and discharge, and a power driven fan interposed in the conduit and arranged below 35 the gunwales.

Another object of the invention is to provide a boat, pneumatically propellable as 40 described, together with pneumatic steering means involving a rotatable arrangement of the air intake or discharge or both, the construction being characterized by the elimination of all parts extending into the water whereby the latter is undisturbed except by 45 the passage of the boat.

Other objects and advantages will appear in the description to follow and will be pointed out in the annexed claims.

The invention, in an illustrative embodi-

ment, is shown in the accompanying drawings, in which—

Figure 1 is a side elevational view of a boat showing the invention as applied thereto;

Fig. 2 is a longitudinal sectional elevation thereof;

Fig. 3 is a plan view of Fig. 1;

Figs. 4 and 5 are longitudinal and transverse sections of the preferred form of fan employed;

Fig. 6 is a diagrammatical plan view illustrative of the steering mechanism;

Fig. 7 is a detail sectional view taken on the line 7—7 of Fig. 6;

Fig. 8 is an elevational view with parts in 65 section of the revoluble intake or discharge member; and

Fig. 9 is a sectional plan view taken on the line 9—9 of Fig. 8.

Referring to these drawings in detail, *a* 70 represents the boat or vessel to be propelled which may, of course, be of any desired form. The type of boat shown for illustrative purposes, a modern speed boat, is, however, a desirable one to employ on account of low resistance presented to the 75 water. The water line and gunwales of the boat are indicated by references *b* and *c*, respectively.

An engine of any suitable type, such as 80 an explosive engine, for example, is shown in conventional form at 10. Engine 10 is directly connected to a fan 11 indicated in conventional form in Figs. 2 and 3. The particular type of fan, which I have found 85 by experiment to be best suited for the purpose, is what is known in the trade as an exhaust fan and one practical and efficient type of such a fan is shown in Figs. 4 and 5. Fan blades 12, of the shape best shown in 90 Fig. 5, are mounted directly upon the crank shaft 13 of engine 10, which shaft extends in overhanging relation into the fan casing 11, as shown. A central axially arranged inlet 14 and a peripheral outlet 15 are 95 formed in the casing 11, as clearly shown in Fig. 4. The shape of blades 12 and that of the interior compartment 16 within which

they rotate, as shown in Figs. 4 and 5, is that at present preferred and at present known to be efficient for the purpose.

A conduit 17 extends from inlet 14 forwardly to the bow of the boat and is connected to an intake member 18 which extends vertically through the deck of the boat and has a horizontally bent end as shown in Fig. 1. Member 18 is sleeved upon the upturned end of conduit 17, as shown in Figs. 8 and 9, and is rotatably supported thereon by any suitable means. For example, a rod 19 fixed to member 18 may be rotatably mounted in a pair of spiders 20 fixed to conduit 17, and a collar 21 may be fixed to the rod to engage the upper spider to provide a vertical support. From the outlet 15, a conduit 23 extends rearwardly closely adjacent one side of the boat to the stern thereof and upon the upturned end of the conduit is a discharge member 24 identical in construction with the member 18 as just described.

Fixed by any suitable means to the members 18 and 24 are drums 25 and 26 which are adapted to be turned by the steering devices. The latter will be best understood by reference to the diagrammatical showing in Fig. 6. A cord 27 is wrapped around drum 25 and fastened thereto at 28. One end of this cord extends rearwardly to and is wrapped around a steering drum 29 and fastened thereto at 30 (Fig. 7). From drums 29 and 25 the ends of the cord are brought to and around drum 26 and fastened together at 31. Cord 27 may be mounted and supported in any of the well known ways, such as by pulleys 32 and eyelets 33 (Figs. 2 and 3). The manner of wrapping the cord about drums 25, 26, and 29 is clearly indicated in Fig. 6, and the arrangement is such that by turning drum 29 members 18 and 24 are turned in opposite directions. Thus, if drum 29 is turned in the direction of the arrow (Fig. 6), member 18 will be turned in a counter-clockwise and member 24 in a clockwise direction. The particular means described for turning members 18 and 24 has been chosen merely as an illustrative embodiment of one operable means and obviously other suitable means may be used as desired to accomplish the same function.

In operation, air is drawn in through member 18 which, it is to be noted, extends above the gunwales *c* and above the highest point of the bow of the boat. Blades 12 revolving at high speed within casing 11 draw in the air through conduit 17 and expel it through conduit 23 and discharge member 24 which also extends above gunwales *c*. Thus, a forward impetus is obtained by both the intake and discharge of the air to propel the boat forward. When members 18 and 24 are set in line as shown by full lines in Fig. 3, the boat is propelled

straight ahead, but by turning drum 29 members 18 and 24 may be swung in unison toward either side of the boat to change its direction. For example, when members 18 and 24 are swung to the position shown by dotted lines in Fig. 3, the boat will be turned to the right. The intake 18 and discharge 24 may moreover be turned through one hundred and eighty degrees from the full line position shown in Fig. 3, so that they face one another, and boat *a* will then be moved backward in a straight line.

The arrangement of parts as described permits the use of a compact power plant and, what is more important, the power plant may be arranged at the desired position within the boat. It may be moved well forward of the boat as shown without difficulty for the long rapidly revolving shaft ordinarily necessary is here eliminated. Moreover, the fan and engine may be located well down in the boat close to its keel in contra-distinction to the earlier types of pneumatically driven boats wherein the fan or propeller had to be exposed to the air and thus mounted above the gunwales, thereby decreasing the stability of the boat.

The invention, as disclosed, is particularly characterized by the absence of propelling and steering means which extend into the water, and the latter is undisturbed except by the passage of the boat. This feature is an important one, particularly when speedy boats are wanted, for it eliminates the churning of and undesirable eddies in the water about the boat. With the present construction, the only resistance encountered is due to the boat's passage through the water.

The invention has been described in a preferred form for illustrative purposes, but the scope of the invention is defined by the appended claims rather than by the foregoing description.

What I claim is—

1. The combination in a pneumatically propelled boat of an air conduit extending from the bow to the stern and arranged below the gunwales of the boat, an exhaust fan interposed in said conduit, means to drive the fan, and intake and discharge members connected to the forward and rear ends of said conduit and extending, respectively, above the gunwales of the boat at the bow and stern thereof.

2. A pneumatically propelled boat having an air intake member at the bow thereof arranged above the gunwales of the boat, an air discharge member at the stern of the boat likewise arranged above the gunwales thereof, a power driven exhaust fan arranged intermediate said members and below the gunwales of the boat, a conduit connecting said intake and discharge members to the inlet and outlet passages of said fan,

one of said members being pivoted to turn on a vertical axis, and means to turn said pivotally mounted member whereby the boat may be steered.

5 3. A pneumatically propelled boat having a power driven exhaust fan located substantially below the gunwales of the boat, intake and discharge conduits extending from the fan and below the gunwales of the boat to

the bow and stern, respectively, intake and 10 discharge members pivotally connected to the bow and stern ends, respectively, of said conduits to turn on a vertical axis and extending above the gunwales of the boat, and means to turn said members in unison to- 15 ward the same side of the boat whereby the latter may be steered.

GEORGE W. CHRISTOPH.
